CLAIM

The ornamental design for a sensor with connector for respiratory circuit, as shown and described.

DESCRIPTION

FIG. 1 is a front view of a sensor for respiratory circuit, as installed within a port of a connector that is connectable to a respiratory circuit.

FIG. 2 is a left elevation view thereof; respiratory circuit shown in FIG. 6.

FIG. 3 is a right elevation view thereof;

FIG. 4 is a rear elevation view thereof;

FIG. 5 is a top plan view thereof;

FIG. 6 is a bottom plan view thereof;

FIG. 7 is a rear perspective view thereof.

FIG. 8 is a front elevation view of the sensor for respiratory circuit shown in FIG. 1, the rear elevation view being a mirror image.

FIG. 9 is a right side elevation view thereof, the left side elevation view being a mirror image;

FIG. 10 is a top plan view thereof;

FIG. 11 is a bottom plan view thereof; and,

FIG. 12 is a perspective view thereof.

The broken line showing of parts of the drawings is included for the purpose of illustrating environment and forms no part of the claimed design.

1 Claim, 11 Drawing Sheets
